CLAIM

The ornamental design for a payment terminal for a fuel dispenser, substantially as shown and described.

DESCRIPTION

FIG. 1 is a front, right side, perspective view of a payment terminal for a fuel dispenser showing our new design;

FIG. 2 is a front view thereof;

FIG. 3 is a right side view thereof;

FIG. 4 is a left side view thereof; and,

FIG. 5 is a top view thereof.

The bottom and rear portion of the payment terminal for a fuel dispenser of FIGS. 1-5 is devoid of surface ornamentation and is not part of the claimed design.

The broken lines shown in the drawings represent portions of the payment terminal for fuel dispenser that form no part of the claimed design.
